ROOM FRONT CONSTRUCTION FOR SAND
BLASTING APPARATUSWilliam A. Rosenberger, Hagerstown, Md., as-
signor to Pangborn Corporation, Hagerstown,
Md., a corporation of Maryland

Application May 2, 1934, Serial No. 723,552

13 Claims. (Cl. 51—8)

This invention relates generally to sand blasting equipment. More particularly it has to do with room front constructions for rooms in which sand blasting operations are carried out.

5 Constructions have been heretofore proposed wherein a room is provided with a front having a vertically movable curtain, the latter having apertures therein through which the work may be observed by the workman standing on the outside 10 of the room. The curtain in such prior constructions has also been provided with a plurality of slits, through which the nozzle may be progressively inserted as the work proceeds.

Although the above mentioned room constructions represent a great improvement over the old practice of having the workman carry out the blasting operation in the same room with the work, they nevertheless possess several disadvantages. One of the major disadvantages of 20 such prior constructions resides in the fact that they are so constructed that the workman is unable to closely follow, or properly inspect, the work, with the result that material is often spoiled. It is moreover necessary, in such constructions, for the worker to support the nozzle and move it over the face of the work as the work progresses, which, especially when coupled with the fact that the worker is able to direct the blast at various angles with the surface of the 30 object being cut, often results in inferior work. Such prior constructions are also inefficient as regards their dust retaining ability with the result that dust gets into the atmosphere and endangers the health of the workmen.

35 It is accordingly a primary object of my invention to devise a novel blasting-room front construction that gives the workman a clear view of the work at all times and which may be readily operated to allow inspection of the work.

40 It is a further major object of my invention to devise a novel blasting-room front construction that will very efficiently prevent dust from escaping from the room where the operation is being carried out, and yet which will permit ready movement of the nozzle over the surface of the 45 work.

It is another important object of the present invention to so construct a room front, having a 50 window therein and a nozzle associated therewith, that the window may be opened without moving or disturbing the nozzle.

Another object of this invention resides in the provision of a blasting-room front with a window 55 which is mounted for rocking movement about a

horizontal axis, to thereby provide ready access to the work.

Another object of my invention is to provide a blasting-room front with means for supporting an abrasive nozzle. 5

It is a further object of the invention to provide a blasting-room front of the character having an opening through which a nozzle may be inserted, with means for supporting a nozzle for guided movement upon the room front so that it 10 will project through the opening and may be moved to various regions of the opening to follow work located in the room.

It is another object of my invention to provide an apertured sand blast room front, through 15 which a nozzle is adapted to project, with means that will prevent sand from escaping from the room by way of the aperture, and yet will not interfere with movements of the nozzle into various regions of the aperture. 20

My invention further aims to devise an apertured blasting-room front of the character having a nozzle manipulating opening provided in a vertical wall thereof, and having means for guiding a nozzle for defined movement into various 25 regions of the opening, and to associate sand baffling means therewith which, disposed in the path of movement of the nozzle, is freely displaceable by engagement of the nozzle therewith as it undergoes movement. 30

It is another object of my invention to devise a supporting mechanism for a sand blast nozzle which is adapted to be moved over the face of the work and maintains the nozzle in a definite angular position with the surface at all times. 35

It is a further object to so design a sand blasting-room front construction having an inspection window and sand baffling members that the window is operable to lift the sand baffling members out of the way and afford full visual inspection 40 of the work when the window is opened.

My invention further aims to devise a supporting mechanism for a sand blasting nozzle that will permit the nozzle to undergo circular motions over the surface of the work but will 45 maintain it in a definite predetermined angle with respect thereto.

It is another object of my invention to provide a sand blasting apparatus of the character having a nozzle mounted for horizontal movement 50 within an opening in a room front, or the like, with a plurality of sets of sand baffling members located in the path of movement of the nozzle, one of the sets terminating adjacent the path of 55 nozzle travel.

My invention also aims to provide sand blasting equipment of the character having a vertically movable frame member, with a transversely movable sand blasting nozzle.

It is another object of this invention to improve the curtain supporting mechanism of sand blast apparatus having a vertically movable curtain, and it is also an object to devise a novel illuminating organization for apparatus of this character.

Further objects of my invention will become apparent as the detailed description thereof proceeds in connection with the annexed drawings, and from the appended claims.

15 In the drawings,

Figure 1 is a perspective view of my novel room front construction with the sand blast nozzle in operative position and it illustrates the inspection window disposed in fully open position, thereby affording visual inspection of the work.

Figure 2 is a fragmental sectional view of the curtain guide structure and it is taken on the line 2—2 of Figure 1.

20 Figure 3 is a view similar to Figure 2, but it is taken on line 3—3 of Figure 1.

Figure 4 is a perspective view illustrating the rear of the room front construction shown in Figure 1 as it appears when detached from the room.

Figure 5 is a view similar to Figure 1, but it illustrates the window disposed in closed or working position.

Figure 6 is a sectional view taken on the line 35 6—6 of Figure 4.

Figure 7 is a sectional view taken on the line 1—7 of Figure 4.

Figure 7A is a sectional view of the counter-weight assembly shown in Figure 1.

40 Figure 8 is an enlarged fragmental elevational view of the frame structure which supports the window, the latter being removed therefrom in this view for sake of clarity.

Figure 9 is a sectional view taken substantially 45 on the line 9—9 of Figure 8, looking in the direction of the arrows.

Figure 10 is an isometric view of a portion of the window supporting frame structure.

Figure 11 is an enlarged elevational view of the 50 window shown in Figure 1, and it is illustrated as being removed from its supporting frame structure.

Figure 12 is a sectional view taken substantially 55 on line 12—12 of Figure 11, illustrating the parts as they appear when viewed in the direction of the arrows.

Figure 13 is a perspective view of the nozzle supporting carriage of the device shown in Figure 1, and it illustrates the nozzle in position 60 thereon and the nozzle guide plates disposed in their separated position.

Figure 14 is a view similar to Figure 13, but it shows the nozzle guide plates as being disposed in their closed position and it also illustrates the 65 manner in which the nozzle and carriage are grasped for manipulating them to carry out the blasting operation.

Figure 15 is a side elevational view of the nozzle supporting carriage shown in Figures 13 70 and 14, and parts thereof have been shown in section for the purpose of more clearly illustrating the structure involved.

Figure 16 is an enlarged sectional view taken 75 on line 16—16 of Figure 15, looking in the direction of the arrows.

Figure 17 is a sectional view of a modified form of room front construction also forming part of my invention.

Figure 18 is a fragmental sectional view of the construction shown in Figure 17 and it illustrates 5 the inspection window as being disposed in partially open position.

Figure 19 is a view similar to Figure 18, but it illustrates the inspection window as being disposed in fully open position, and 10

Figure 20 is an enlarged sectional view of the curtain shown in Figure 17, and it illustrates the manner in which the stiffening members are secured thereto.

With continued reference to the drawings, 15 wherein like reference characters are employed to designate like parts, through the several views thereof, my novel sand blasting room front construction consists of a frame structure designated generally as A, a movable frame member B, 20 which is supported for vertical movement on a curtain which carries an inspection window C and a sand blasting nozzle supporting carriage E. The frame construction will now be described.

The frame is constructed of a pair of vertical 25 members 11, which are generally channel shaped and are rigidly joined by horizontal plate members 12 and 13. With particular reference to Figures 1 and 7, plate 13 is provided with a forwardly extending flange 14. Secured to flange 30 14, by means of bolt and nut assemblies 15, is a horizontally extending plate 16. The ends of plate 16 are secured to angle pieces 17 which are riveted or otherwise secured to the upper ends of channel members 11. An angle member 18 35 is secured to the rear edge of plate 16 by means of bolt or nut assemblies 19 for the purpose of stiffening it, and preventing it from flexing in service.

Secured to the lower edge of plate 13, by means 40 of bolt and nut assemblies 21 and a binding strip 22 is a flap 23, which is preferably constructed of a piece of rubber-impregnated fabric. Flap 23 is adapted to cooperate with the curtain and function as a baffle for minimizing the escape of 45 abrasive or dust laden air from the upper part of the room in a manner that will be pointed out hereinafter.

With particular reference to Figures 4 and 6, the upper edge of plate 12 is provided with an 50 inclined flange 28, and connected thereto by means of bolt and nut assemblies 29 and a binding strip 31 is a flap member 32, which is similar to flap 23 and is adapted to cooperate with the curtain and minimize the escape of abrasive 55 material from the lower part of the room in a manner that will be hereinafter described.

The frame construction just described is adapted to be secured to the floor of the building in which the apparatus is used by any desired form 60 of securing means which may be associated with a forwardly extending flange 33 formed on plate 12, and with a pair of angle pieces 34 connected to channel members 11.

The curtain structure is adapted to be guided 65 for vertical movement by means of guides provided on the front of the frame structure just described, and the construction of the right hand guide shown in Figure 1 will now be described.

Referring more particularly to Figure 2, a 70 metal strip 35 and a guide plate 36 are secured to the front flange of member 11 by means of bolt and nut assemblies 37. Strip 35 functions as a spacer member, and as seen in Figure 2, it spaces guide plate 36 sufficiently from flange member 11 75

to provide a channel or guideway therebetween. The left hand guide construction is shown in Figure 3 and is somewhat similar to that just described, except that an angle member 38 is also secured to the face of guide plate 36 by means of bolt and nut assemblies 37. The forwardly extending flange 39 of member 38 forms a guide for the counterweights that will be hereinafter described.

Secured to the upper end of guide 36 is an angle piece 41, and a similar angle piece 42 is secured to the lower end of member 38. Angle pieces 41 and 42 are adapted to function as upper and lower window-frame stops respectively in a manner that will be hereinafter pointed out.

The frame construction just described is adapted to be secured in any suitable form of sand blasting room structure by means of suitable fastening means extending through apertures 43 formed in the rear flanges of members 11. The room construction may take any desired form, and as it forms no part of the present invention it has not been disclosed. It, however, preferably takes the form of an enclosure having a door located in a side thereof so that the piece of work that is to be operated upon may be introduced therein on a truck or the like, or it may be provided with an opening in the ceiling to allow the work to be handled by a crane or the like. An exhaust fan is also preferably associated with the room for removing the dust laden air therefrom. The present room front construction is adapted to be employed with a room having a door in the side thereof, and to this end a door latch keeper 44 is secured to right hand member 11 for cooperating with the door of the room.

As previously indicated, frame B is adapted to be supported by a vertically movable curtain, and although the curtain may take any suitable form, I preferably employ a two-part, roller supported curtain that will now be described.

With reference to Figure 1, a pair of brackets 45 are secured to members 11 as by means of bolt and nut assemblies, and a roller 46, having a flange 47 provided on the left hand end thereof is journaled in brackets 45 in any suitable manner. If desired, anti-friction bearings of any suitable construction may be associated with brackets 45 and roller 46 so that the latter may operate with a minimum of friction. A curtain 48 is attached to roller 46 in any suitable manner and extends downwardly in the guides and is connected to frame B in a manner that will be described hereinafter.

A pair of brackets 49 are secured to the lower ends of members 11 and an idler roller 51, and a curtain carrying roller 52 are journaled therein. Roller 52 is provided on its left hand end with a flange 53 which cooperates with the curtain counter-balancing mechanism. A curtain 54 is secured to roller 52 and extends under idler roller 51 and upwardly between the guides defined by guide plates 36 and is connected to frame B as will be hereinafter described.

Although I have disclosed rollers 46 and 52 as being disposed in front of the construction, or exteriorly of the room, it is to be understood that either or both of them may be located within the room and a satisfactorily operating mechanism obtained. Moreover, curtain 54 may be wound on roller 52 in a direction opposite that disclosed and idler roller 51 dispensed with, but I preferably employ the construction disclosed as it insures freeing substantially all of the sand from

curtain 54 before it is wound upon roller 52 in a manner that will be described hereinafter.

Frame B is accordingly mounted for synchronous movement with curtains 48 and 54 and I preferably provide the device with mechanism for counterbalancing the weight of frame B and its associated parts, and for also insuring that the curtain will be wound up on one roller as it is unwound from the other, and the mechanism that I preferably employ for attaining this result will now be described.

A cord 55 of any suitable character is connected to roller 46 and supports a counter-weight carrying member 56 at its lower end. A plurality of counter weights 57 are carried by member 56 and are provided on their rear faces with recesses which embrace flange 39, and are adapted to be guided for vertical movement thereby. Member 56, Figure 7A, is preferably hollow and a spring 58 is disposed therein, and is connected thereto by means of a bolt 58'. Connected to the lower end of spring 58, is a threaded member 59, to which a hook member 60 is adjustably connected by means of a nut assembly 61. A cord 62 is connected to roller 52 and is secured to the lower portion of member 60. Cords 55 and 62 are wound upon rollers 46 and 52 in the proper direction to produce proper rotation thereof, as shown in Figure 1.

The mass of counter-weights 57 is preferably calculated to approximately equal the mass of frame B and its associated parts and also the unwound portions of curtains 48 and 54, in order to insure smooth operation with a minimum of effort on the part of the operator. Spring 58 is preferably interposed between cords 55 and 62 in order that the latter may be maintained taut at all times despite the changing effective radii of rollers 46 and 52 as curtains 48 and 54 are wound upon and unwound therefrom.

As previously stated, frame B carries the nozzle supporting carriage and the inspection window and the construction of frame B will now be described. With reference to the Figures 1, 8, 9 and 10, an angle member 63 is secured to curtain 48 by means of bolt and nut assemblies 64 and a binding strip 65. Member 63 is provided with a horizontal portion 66 and a vertical portion 67, which, as seen in Figure 8, terminates short of the sides of curtain 48. The other ends of binding strip 65, and the vertical portion of member 63 to which the binding strip is secured define guide members which are adapted to ride in the frame guides. Flanges 68, of a pair of vertical angle members 69, are secured to member 63 at 70 as by means of butt welds or the like. Front flanges 71 of members 69 lie in the plane of, and are secured to, the front vertical portions of member 63 by means of welds 72. Flanges 68 of members 69 are provided with aligned apertures 74, which are adapted to pivotally support the inspection window structure that will be hereinafter described. Aligned with apertures 74 are a pair of bearing members 75, which are secured to flanges 68 of members 69 by means of welds 76.

The bottom of frame B is preferably defined by a channel member 78, having upper and lower carriage supporting and guiding flanges 79 and 81 respectively. The mid portion of member 78 is preferably disposed in the plane of flanges 71 of members 69 and is secured thereto at either end at 82, by means of welds. A plate 83, which is also preferably disposed in the plane of portion 71 of member 69, is preferably secured to member 78 by means of welds 84 and 85, and is secured 75

to the lower ends of members 69 by means of welds 86.

Member 78 is reinforced against twisting with respect to the frame by means of a pair of plates 87 which are secured thereto by means of welds 88. Plates 87 are secured to flanges 68 of members 69 by means of welds 89. A plate 91, preferably disposed in the plane of flanges 79 and 81 of member 78, is preferably secured to the latter by means of welds 92. Plate 91 cooperates with member 78 so as to constitute a tubular section, thereby greatly increasing its resistance to flexing or twisting under the loads imposed upon it during operation.

15 A pair of dogs 94 are pivotally connected to portions 68 of members 69 by means of pins 95, and are adapted to restrain the nozzle supporting carriage from inadvertent removal from the device in a manner that will appear hereinafter.

20 Curtain 54 is secured to member 83 by means of a bolt and nut assembly 96 and a binding strip 97.

Frame B is accordingly mounted for vertical movement in the guides defined by the front flanges of members 11 and guide plates 36, the frame being guided at its upper end by the extremity of clamping strip 65 and the end of the vertical flange of member 63, and is guided at its lower end by the ends of clamping strip 97 and member 83. The parts just described fit fairly closely in order to prevent frame B from undergoing tilting movements when it is raised and lowered, so that the nozzle carried thereby will be maintained at a definite angle with respect to the work. Movement of frame B is preferably limited as it is raised and lowered by means of a lug member 100, which is secured to flange 70 of member 69, and is adapted to cooperate with angle pieces 41 and 42. Although I have illustrated curtains 48 and 54 and frame B as being mounted for movement in common guides, and I prefer to employ this structure, they may, if desired, be mounted in individual guides without departing from the spirit of my invention.

Nozzle carriage D is mounted for horizontal movement on member 78, and, although it may assume any desired configuration, it is preferably constructed of a flat metal plate 101. Plate 101 is supported on flange 79 by means of a pair of wheels 102, and it is restrained against tilting and upward movements with respect thereto by means of a lower wheel 102 which cooperates with flange 81 of member 78.

Wheels 102 are identical in structure and, as they are secured to plate 101 in a similar manner, similar reference characters have been applied to the parts thereof and only one of them will be described. Wheels 102 are flanged as seen in Figure 15 and they are rotatably journaled on shouldered bolts 103. Upper bolts 103, extend 60 through apertures in plate 101 and are secured thereto by means of nuts 104, while lower bolt 103 extends through a vertical slot 105 located in plate 101. Wheels 102 are centered on bolts 103 by means of bushings 106 and 107. The enlarged portions of bolts 103 are so designed that, when nuts 104 are turned home, wheels 102 and bushings 106 and 107 will have sufficient play for proper operation. It is apparent that, by loosening nut 104 associated with the lower wheel, the entire lower wheel assembly may be moved vertically in slot 105 to increase or decrease the clearance between the wheel assemblies and member 78.

Upper wheels 102 are preferably enclosed in 75 metal housings 108 which are provided with ears

109. Housings 108 are adapted to be drawn up into surface engagement with the rear face of plate 101 by means of bolts 112 and nuts 111. Housings 108 function to prevent sand from getting at upper wheel assemblies 102, thereby insuring proper operation thereof.

Plate 101 is accordingly mounted for horizontal movement on rail member 78 and it may be, if desired, removed therefrom by lifting dogs 94 and moving the carriage away from rail 78. With 10 reference to Figures 13 and 14, a handle 113 is secured to plate 101 and is adapted to be grasped by the operator for shifting the carriage. In Figure 15, a modified form of handle 113a is disclosed which extends rearwardly and is secured 15 to the rear face of plate 101 by a welding operation.

Plate 101 is provided with a preferably circular aperture 116, through which the sand blast nozzle is adapted to be inserted.

20 The nozzle supporting mechanism will now be set forth. A pin member 117 extends through an aperture in plate 101 and is secured thereto by a weld 118 on the rear face of plate 101. A lever 119, having an elongated hub portion 120, 25 is journaled on pin 117 and is secured against endwise removal therefrom by means of a cotter pin 121 or the like. A torsion spring 122 is mounted on hub 120 and its front end is provided with a hook portion 123 which is adapted to be 30 looped under lever 119. The other end of spring 122 is provided with a hook portion 124 which is adapted to be selectively engaged with one of a plurality of apertures 125 located in plate 101. A plurality of apertures 125 are provided so that 35 the tension of spring 122 may be adjustably varied by inserting portion 124 thereof into the proper aperture in plate 101.

A nozzle supporting member 126, having a nozzle receiving aperture in its upper end and a 40 clevis at its lower end, is pivotally connected to lever 119 by means of a pin 127. A nozzle assembly, designated generally as 128, has a supply pipe 129 connected thereto and extends through and is adapted to be secured in the upper end of link 126 by means of a pair of set screws 132 or the like. The nozzle assembly proper consists of a nozzle pipe, a nozzle connector and a nozzle, but, as it forms no part of the present invention, and, as any type of nozzle construction may be 45 used with my nozzle supporting construction, it will be referred to generally hereinafter as nozzle 128 and it will not be further described.

Nozzle 128 extends through aperture 116 in plate 101 and is normally urged upwardly by 55 spring 122, which is preferably adjusted to counterbalance the weight of the nozzle assembly and the portion of pipe or hose 129 that is normally supported above the floor, so as to insure vertical movements of the nozzle with a minimum of 60 effort.

With the parts adjusted as seen in Figure 13, nozzle 128 may be moved over a circular area defined by the area of aperture 116, and be directed against the work designated as E (Figure 1) and 65 which, in the present instance, is a tombstone or the like. When it is desired to direct the blast over a greater horizontal area of the work, handle 113 may be grasped and the carriage moved to the right or left. On the other hand, if it is desired to direct the blast against a greater vertical area of work than aperture 116 will permit, nozzle 128 is lifted upwardly until it contacts the upper wall of aperture 116. Upon further force 70 being applied, either through handle 113 or nozzle 75

128, it is transmitted to the carriage, to frame B, and thence to curtains 48 and 54, with the result that the frame is lifted vertically, and curtain 48 is wound up on roller 46 and curtain 54 is unwound from roller 52. If it is desired to move the assembly downwardly over the work, downward forces are applied to the nozzle and handle 113 so as to cause frame B to move bodily downwardly.

10 It is sometimes desirable to limit the nozzle to solely vertical movement or to movement over a comparatively narrow vertical area and I have accordingly provided plate 101 with a pair of guide plates 133, which are mounted on plate 101 15 for adjustment toward and away from each other and they are adapted to cooperate with the sides of nozzle 128 in a manner that will be hereinafter described. Plates 133 are secured to plate 101 by means of adjustable bolt and nut assemblies, 20 and as they are identical in character, only one of them will be described. Referring more particularly to Figure 16, a pair of vertically spaced slots 134 are formed in plates 101 and extending therethrough are a pair of screws or bolts 135. 25 Rectangular lug members 136 are received in recesses 137 formed in screws 135 and are welded or otherwise secured thereto. Lugs 136 cooperate with the side walls of slots 134 and prevent rotation of screws 135 in response to adjustive 30 manipulation of nuts 138, which are threaded thereon.

When it is desired to guide nozzle 128 for vertical movements, nuts 138 are loosened and plates 133 are brought into the relation shown in Figure 35 14, in close proximity to nozzle 128. Nuts 138 are then tightened and the device is ready for operation. As seen in this figure, handle 113 is preferably grasped by the left hand and the nozzle grasped by the right. The operator is thereby 40 able to produce vertical movement of the nozzle with his right hand, and when the particular vertical area of the work has been completed he is able with his left hand to move the carriage a sufficient distance to the right or left to bring a 45 new area into cooperating relationship with the nozzle.

I preferably associate illuminating means with my improved construction, which, in the present instance, takes the form of an electric lamp bank, 50 and in order to insure that the illumination remains of constant value at all times, I preferably mount the lamp bank on frame B, so that it may move up and down with the latter, and accordingly follow the nozzle over the face of the work.

55 With reference to Figure 4, a plurality of brackets 141, supporting a plurality of lamps 142, are secured to horizontal flange 66 of frame member 63. Lamps 142 may be of any desired construction and they are supplied with electricity by 60 means of a conductor 143 which extends through a conduit 144 and is connected to each lamp in any well known manner. Conductor 143 hangs in a loop from the end of the conduit, and extends through an aperture in frame member 11. The 65 loop is provided so that frame B and the lamp assembly may undergo vertical movement without interference from conductor 143. Conductor 143 extends outwardly of frame member 11 and is associated with a switch 145 and a lead-in conductor 146, the latter being adapted to be connected to any suitable source of electric power (not shown).

The opening provided in frame structure B is 70 provided with a preferably pivoted inspection window having a transparent portion through

which the work may be observed and also a portion having sand deflecting baffles which permit ready operative vertical and horizontal movements of the nozzle and yet efficiently prevent abrasive material from escaping from the room. 75 In this form of my invention, this window preferably takes the form of a window structure mounted for pivotal movement upon a horizontal axis, and it will now be described.

With particular reference to Figures 11 and 12 10 of the drawings, a pair of horizontally extending angle members 149 and 151 are secured, as by welding or the like, to a pair of end plates 152, thereby defining a generally rectangular frame. Secured to member 149 in any desired manner is 15 an angle member 153. Secured to the depending flange of member 151, by means of a bolt and nut assembly 154 and a binding strip 155, is a screen 156 which is preferably of relatively fine mesh. The lower edge of screen 156 is secured to member 153 by means of a pair of clamping strips 157, a bolt and nut assembly 158 and a plurality of washers 159. Washers 159 are disposed between member 153 and the clamping strip assembly in order to space the lower edge of the screen from 20 member 153. Accordingly any sand or other abrasive that might find its way through screen 156 will drop and rest upon member 153 and can accordingly find its way out beneath the binding strip assembly and will not build up between the 25 screen and the glass. The ends of screen 156 are held in place by binding strips in a similar fashion.

Preferably a plurality of comparatively thick 30 panes of glass are disposed in the frame and lie 35 against member 153 at their lower edges and against the depending flange of 151 at their upper ends. Panes 161 are maintained in proper assembled position by means of an angle bar 162, which is secured to member 151 by means of bolt and 40 nut assemblies 163. The lower ends of panes 161 are restrained against outward movement by means of a retaining strip 164 which is secured to member 149 by means of screws 165.

Secured to the depending flange of member 45 149, by means of nut and bolt assemblies 166 and a clamping strip 167, are a plurality of short flaps 168 and 168a and a plurality of longer flaps 169 and 169a. Although flaps 168 and 169 may be disposed in alignment if desired, I preferably 50 stagger them in order to reduce escape of abrasive to a minimum. Pivot pins 170 extend through apertures 171 located in end plates 152 and are adapted to be journaled in apertures 74 of member 69. A pair of nuts (not shown) are 55 threaded on pins 170 and are preferably taken up sufficiently to provide adequate friction to hold the window assembly in any adjusted position. Washers 172, preferably constructed of non-metallic material such as leather or fiber or the 60 like, are preferably mounted on pivot pins 170 and serve to space the window structure from the frame structure. When the window is in place in the frame, portions 173 of the window are adapted to contact and be stopped by depending 65 flange 67 of member 63.

Referring now to Figure 5, it is seen that nozzle 128 extends through flaps 168 and 169 and that flaps 168 terminate near the path of travel of the nozzle, with the result that, when the carriage 70 is moved horizontally, the nozzle sweeps aside substantially only a single set of flaps, with the result that resistance to movement of carriage is small. Flaps 168a and 169a, located at the extreme ends of the structure, are made wider for 75

the reason that it has been found that their greater inherent tendency to remain flat prevents them from wedging themselves in between the guides and other moving parts of the construction.

The operation of my device is as follows. The stone or other work is placed within the room, switch 145 is operated to provide illumination for the work, and handle 113 and nozzle 128 are grasped and manipulated in the manner previously described, to move the nozzle over the face of the work. While the work is progressing, the operator sights through windows 161 and visually follows the steps thereof. When it is desired to make a closer inspection of the work or obtain a measurement or a physical inspection thereof, the lower edge of the window is pushed inwardly to thereby rock it in a counter-clockwise direction (Figure 12) away from stop flange 67. If desired the window may be rocked in this direction through an angle of 180° to obtain a small inspection opening or the workman may rock it through an angle of substantially 270° into the position illustrated in Figure 1 to obtain a full view of the work. As movement of the window in this manner lifts the flaps away from the nozzle, the inspection operation does not disturb the latter. Referring to Figure 1, it is seen that movement of the window into the position shown has brought the flaps on the top side thereof. In view of the fact that the window is pivoted off center (Figure 12) it may readily clear flange 67 and be brought into this position.

In order to releasably maintain window C in the position shown in Figure 1, dog or latch member may be provided, but I preferably attain this result by tightening pivots 170 sufficiently when assembling the machine so as to compress washers 172 and provide enough friction to hold the window in any desired adjusted position.

Although I have illustrated and prefer to employ a nozzle support that maintains the nozzle in a position that is normal to the face of the work, in order to prevent the worker from under-cutting the stone or other material that is being handled by the apparatus, it is to be understood the nozzle may be held in other positions on the support, or in fact other types of nozzle supports may be mounted on carriage D without departing from the spirit of my invention.

As the curtain is moved vertically, flaps 23 and 32 cooperate therewith to maintain a substantially tight seal to prevent the dust laden air contained in the room from getting into the atmosphere. As flap 32 is inclined, any sand or dust that may drop downwardly is deflected away from curtain 54 thereby. It is also observed that, as curtain 54 is wound upon roller 52, sand or other foreign material cannot be carried thereon as the horizontal reach of curtain 54, formed by idler roller 51, functions as a shelf or a baffle member. Moreover, as curtain 54 passes over idler roller 51, any sand that may be adhering to the rear face of the curtain is removed therefrom as the comparatively small diameter of the idler roller causes the pores of the material to open up during this operation.

Although I have illustrated the sand baffling flaps as being secured to a window that is pivoted for work inspection movements, it is to be understood that the flap construction may function equally well with any other window whose lower edge is adapted to be lifted as it is opened, for instance, window C may be supported upon links or be mounted for vertical sliding movement in

frame B, in either case the flaps would be lifted out of the way when the window is raised for inspection of the work. On the other hand, the window may be mounted for downward movement on frame B, and in such case the flaps would move downwardly behind curtain 54 when the window is opened, and the appended claims are intended to embrace my construction when the parts are related in this manner. Moreover, the panes or the screen may be omitted from the window and a satisfactorily operating structure obtained, but I preferably employ the glass-screen combination as the glass panes positively prevent dust from passing through the window, and the screen protects the glass from flying chips of 15 stone.

The sand baffling flaps have been shown as attached to the window and this is a highly desirable arrangement for the reason that when the window is opened the flaps are lifted clear and afford full vision of the work, but it is to be understood that, if desired, the flaps may be mounted on a separate movable frame which is actuated by window opening movements to lift the flaps out of the way and afford inspection of the 25 work without departing from the spirit of my invention.

Although I have shown my window and baffle flap construction as associated with a vertically movable curtain, it is to be understood that it 30 may be stationarily mounted in a room or like front when the work handled by the apparatus is of such dimensions that it does not require great vertical nozzle movements and the appended claims are intended to embrace my construction when it is used in this manner.

Referring now to Figures 17 to 20, inclusive, I have illustrated a modified form of my invention and in order to clarify the disclosure, certain parts which are similar to those employed in the 40 first form of my invention, such as the lamps, the nozzle, and the nozzle carriage, have been omitted. In this form of the invention, frame members 11a are interconnected by lower and upper members 12a and 13a respectively. Mounted for vertical movement within the guides located on members 11a is a main frame structure 176. A window structure 177 is pivoted at 178 in the main frame, and connected to the lower end thereof are a plurality of flaps 168b which function in a manner similar to those employed in the first form of my invention.

A pair of cords 179 are connected to the main frame at lateral spaced points and extend upwardly over pulleys 181, which are supported on 55 the room and are connected to counterweights 182. Upper curtain 183 is connected to member 13a at its upper end and rests on the top of main frame 176. A lower curtain 184 is connected to the lower side of the main frame and extends 60 downwardly and rests upon member 12a. Curtains 183 and 184 are preferably stiffened by means of rods 185 which are secured thereto by means of casements 186 which may be stitched or otherwise secured to the curtain. Curtains 65 183 and 184 preferably are guided in the same guides that accommodate frame 176, and it is observed that, as the frame moves upwardly, the upper curtain folds up in an accordion formation on the top of the frame, and the lower curtain 70 is extended, whereas, when the frame is lowered, the upper curtain is extended and the lower curtain folds up into an accordion formation on member 12a.

When it is desired to inspect the work, the 75

window 177 may be swung into the partially opened position shown in Figure 18, or it may be rocked through substantially 270° into the position shown in Figure 19, which gives the 5 maximum opening.

The invention may be embodied in other specific forms without departing from the spirit or essential characteristics thereof. The present embodiments are therefore to be considered in 10 all respects as illustrative and not restrictive, the scope of the invention being indicated by the appended claims rather than by the foregoing description, and all changes which come within the meaning and range of equivalency of the 15 claims are therefore intended to be embraced therein.

What is claimed and desired to be secured by United States Letters Patent is:

1. In a room front construction, upper and 20 lower members disposed substantially in a vertical plane, said members being vertically spaced to provide a horizontally extending opening therebetween, a horizontally extending window disposed in said opening and mounted for rocking 25 movement about a horizontal axis; an abrasive baffling curtain connected to said window and depending downwardly therefrom into a position immediately adjacent the rear face of lower member when said window is closed, said 30 window being operable to lift and also move said curtain further to the rear of said lower member when said window is opened.

2. The construction described in claim 1, wherein said window is mounted for rocking 35 movement through an angle greater than 180°, whereby it may be rocked to bring said curtain onto the top side thereof.

3. The construction described in claim 1, wherein said window is automatically operable 40 to restore the depending portion of said curtain to its position adjacent the rear face of said lower member when it is moved from open to closed position.

4. The construction described in claim 1, together with means for effecting synchronous vertical movement of said upper and lower members and said window.

5. In a room front construction, an upper member and a lower member disposed substantially in a common vertical plane, said members being vertically spaced to provide a horizontally extending nozzle manipulating opening therebetween; a horizontally extending inspection window disposed in said opening and operable 55 to close the upper portion of said opening when it is closed, means for mounting said window for rocking movement about a substantially horizontal axis located intermediate the top and bottom edges of the window, whereby said window projects a minimum distance forwardly of the plane of said members when it is opened; and a flexible abrasive baffling curtain secured to said window and adapted to depend therefrom.

6. The construction defined in claim 5, wherein said window is operable to rock through an

angle of substantially 270°, whereby the depending portion of said curtain may be brought up and supported thereby.

7. In a room front construction, an upper member and a lower member disposed substantially in a common vertical plane, said members being vertically spaced to provide a horizontally extending opening; a guide mechanism mounted adjacent the front face of the upper edge of said lower member; an abrasive blasting 10 apparatus supported upon said guide mechanism for movement into various lateral positions; a window disposed in said opening and mounted for rocking movement about a horizontal axis; a flexible abrasive baffling curtain secured to said 15 window and having a depending portion disposed adjacent the rear face of the upper edge of said lower member when said window is closed, said window being operable to lift said curtain and move it rearwardly of said lower 20 member and said abrasive blasting apparatus when it is moved into open position.

8. In an abrasive blasting device supporting mechanism, a horizontally disposed guide member comprising a U-shaped element having an 25 outwardly directed flange on each leg thereof, said flanges being disposed in a common plane; and a carriage, equipped with rollers for engaging each of said flanges, mounted for horizontal movement on said guide element.

9. The mechanism described in claim 8, together with an elongated plate rigidly secured to said guide element and disposed substantially in the plane of said flanges.

10. In a room front construction, a pair of vertically spaced rollers having an apertured curtain rolled thereupon; a hollow counter-weight supporting member connected to the upper of said rollers; and a tension spring disposed within said supporting member and connected to the 40 lower of said rollers.

11. In an abrasive blasting room front construction, a front structure, a frame mounted for vertical guided movement upon said structure, an extensible and contractible curtain secured to 45 the top of said structure and sealingly associated with the top of said frame, said curtain being adapted to fold upon itself when said frame is moved upwardly in its guides together with means for causing said curtain to fold in definite lines 50 when said frame is moved upwardly.

12. A window assembly for use with a room front construction, comprising a frame member, a transparent pane and a screen mounted in said frame member, said screen being disposed in 55 sealing relation to said frame at its top edge and spaced therefrom at its lower edge, to thereby permit abrasive that passes through said screen to escape from between the latter and said window.

13. The construction described in claim 12, wherein the lower edge of said frame inclines downwardly away from said window and screen, for conducting abrasive away therefrom.

WM. A. ROSENBERGER.
